J. Goulding.

Loom.

Patented Jul 7, 1830.

No 4.

John Goulding

Seths Town. Dated, July 7, 1830.

(The Schedule referred to in these Letters Patent and making part of the same, containing a description in the words of the said John Goulding himself of his Improvement in the mode of making and using Looms.

Be it known that I the said John Goulding, have invented constructed, made and applied to use, a new and useful improvement in the mode of making and using looms for weaving.

The particular improvement is set forth in the Schedule and drawings annexed, that is to say,
 A. is the Frame, B is a breast Beam, C. Lays or busters, D. Cloth Beam, E. Yarn Beam, F. Back beam or roller for cloth to pass over, G. Main carbure to form H H. two teeth blocks of wood or metal, these blocks are shown in full size at W W. Those blocks are hung by means of two upright pieces by male and female centres as shown. Those upright pieces are fastened to the rod J, that passes across the loom to hold the other blocks, the other side of the loom between the breast beam and lay, there is a Reed with twelve or more dents, placed the same distance apart, as those teeth in blocks H H. these reeds are placed in the lay at the out or side of the cloth on each side and the blocks placed directly in front, so as to pass freely between the sets in the reed, where the lay or buster comes up where the cloth is made, those teeth are made to pass in through the Reed.

nearly one inch if there is no obstruction. The obstruction if any will be the filling as well as the shuttle passes through the web into the box, in that case the filling will come between the Blocks and Reeds and will carry the Blocks forward with the lay, in so doing it carries forward the upright pieces T1 they being attached to the Rod J. it turns that and there being a lever attached to it at K, a small lever L goes through the end of K lifts it up so as to prevent it hitting an iron placed in the lay for that purpose, provided there is no filling passed from the shuttle, the blocks pass freely into those Reeds, they not being carried back prevents the lever being lifted up over the iron over the lay, likewise the end of the lever hits and the Lay carries it forward, in so doing it strikes at the other end a knee or lever, that is connected with the handle M, so it throws the loom out of gear and it stops it by the lay not carrying up those blocks. These blocks are placed so as to clear the top of Race board, they are held up at one end by T1, and at a little distance rest on a piece of iron made fast to the Breast Beam so as to keep them in a horizontal position but yet hangs so as to work backward and forward horizontally freely by the motion of the lay, if the filling is at either side supplied by the Shuttle shuttle the filling be found to drop below those blocks, there may be a small plate of iron or wire passed from the under side of the blocks over the top of the lay or race board through one of those partings in the Reed, so that when the Lay comes up, it will raise the web up between the blocks and Reeds. This piece must fall into the

7/7/1830 6061X

550

place board of the loy so that the shuttle may pass over it freely. If the loy should not come up accurately there must be a support at each side of the loy to bring it into the proper place; when it arrives at the place where these blocks enter the loom.

In figure No. 4. & Loom frame. b is a breast beam c loy or beater d d. upright pieces of iron fastened to the breast beam, at each end with a pivot so as to turn freely. e e is a small wire fastened to d d, so as the ends m m, can rise and fall freely. these ends m m, that turn downwards is for the purpose of the weft or filling to wind around when the shuttle passes across the web; by the yarrow winding round it draws the wire up to the selvage or edge of the cloth; in so doing it turns in its centre, turns f f. draws b. connecting wire, b, being attached to g draws or turns g, so as to prevent it from hitting g, when the loy comes up to where the cloth is made, now providing there is no filling or weft in the shuttle it will prevent m, from being drawn up to the selvage; likewise prevents f from being moved. f not being moved g, does not move, so when the loy comes up to where the cloth is made or nearly up, ^{at the long end and vice versa} it will strike g, forward and hit a knee that is connected with the handle of the loom, that stops and starts, the loom; in so doing the loom will be stopped. g, hangs on a pin in the centre so that it can vibrate fore and aft, and backwards and forwards it must have a spring attached to it, so as to relieve it from the edge of the cloth, when the weft is wound round the wire at m, the loy or beater comes up, the place board strikes the wire c two inches

from m, and raises it up and liberates the end m, from the woft, when the lay returns back again this falls into its proper place again. The ends m, must fall about half an inch forward to where the cloth makes, likewise an inch or more from the selvage or list of the cloth.

It is a small cone drum, on the main arbor that has a band P which passes round it and round another cone drum on the arbor Q. Arbor Q, has a worm in the outer end and goes into the shaft Q, shaft Q has a worm that takes into wheel R, on the yarn beam. These cone drums are for the purpose of regulating the yarn coming off the beam, the band is shifted in the same ratio that the worm does the size of the beam. To increase the motion of the beam it is done by a lever S that has a bearing at one end against the beam, and the other end is a chain attached to it, and from thence down to a pulley on the arbor T, a chain is attached to another pulley on the arbor V and thence to slide T, slide T has two guide pins, that guide the band P, slide T has a weight X, that brings up the lever S against the yarn beam. This lever S has a bearing in the middle or nearly so the proportion of other parts may require, there may be a shift gear on shaft Q at bottom that plays into the worm on shaft Q, so as to give any number of pieces of woft in an inch required.

What I claim as my invention and for which I herein claim Letter Patent, is the method herein described by which it may be ascertained if the picking or woft breaks while running off from the bobbins or the bobbins deliver off, and by

7/7/1830

557

which ever case of it so breaking or running off, the
farm will be stopped by the apparatus above specified.

In testifying that the above is a true specifica-
tion of my said improvement as above described, I have
hereunto set my hand and seal this fifth day of May
in the year of our Lord one thousand eight hundred and
thirty.
